UNITED STATES PATENT OFFICE.

FRITZ LOWENSTEIN, OF BROOKLYN, NEW YORK.

ELECTRIC SADIRON.

1,333,722.

Specification of Letters Patent. Patented Mar. 16, 1920.

Application filed June 2, 1917. Serial No. 172,414.

To all whom it may concern:

Be it known that I, FRITZ LOWENSTEIN, a citizen of the United States, residing at Brooklyn, county of Kings, and State of New York, have invented certain new and useful Improvements in Electric Sadirons; and I do hereby declare the following to be a full, clear, and exact description of the invention, such as will enable others skilled 10 in the art to which it appertains to make and use the same.

This invention relates to pressing apparatus, and particularly to power operated sad irons. In its more specific aspects, the 15 invention has to do with sad irons in which pressure of the iron against a suitable supporting buck or board is attained by electromagnetic means.

Broadly described, the invention consists 20 in pressing apparatus, such as a sad iron, capable of exerting heavy pressure on material such as cloth or the like spread upon an ironing buck or board, the arrangement being such, however, that the operator may 25 lift the sad iron from place to place on the goods in the customary manner without any more effort, and it may be with less effort, than in manipulating an ordinary light-weight sad iron. Where the sad iron or 30 other pressing device is arranged to be pressed against the goods by power means of some kind, the operation of the power means is so controlled by appropriate mechanism that power pressure is automatically applied by the act of the operator 35 in placing the device against the material to be pressed; said power pressure being automatically discontinued when the operator releases the device, or when he exerts 40 upon the device a force tending to move it away from the buck or other abutment means with which the device is designed to coöperate. In other words, the operation of the device, so far as is apparent to the operator, involves merely manipulating the 45 dead weight of the pressing device, the application and release of the power pressure being controlled automatically by the operator's acts in effecting such manipulation.

50 While the invention, broadly considered, is not limited to a construction involving electrical pressure-applying means, the prin-

ciples of the invention can conveniently be further explained in connection with the sad iron shown in the accompanying drawings 55 and hereinafter described in detail. It is to be understood that this specific disclosure is not to be construed as defining the limits of the invention but that it merely illustrates one type of device within the scope thereof. 60 In the drawings:

Figure 1 is a plan view of the sad iron with the cover and handle grip removed;

Fig. 2 is a side elevation, the cover being partly broken away to disclose the interior 65 construction;

Fig. 3 is a similar view of the iron from one end;

Figs. 4 and 5 are details, in plan and sectional elevation, respectively, and on a 70 larger scale, of a suitable form of make and break device;

Fig. 6 is a transverse section on the line 6—6 of Fig. 2;

Fig. 7 is a detail, partly in section, of a 75 part of the under side of the cover;

Fig. 8 is a detail section on the line 8—8 of Fig. 6; and

Fig. 9 is a diagram of the wiring and connections.

Referring to the drawings, 10 is a smooth bottom plate or pressing surface of copper or other suitable diamagnetic material possessing the requisite heat conductivity; and 11 is an iron casting or forging which forms 85 a magnet core whose relatively thick broad body or intermediate portion lies close to the bottom plate but is slightly spaced away therefrom to provide room for a winding 12 of asbestos-covered magnet wire. The broadened flat terminal portions or poles 13—14, of the core are firmly clamped into positive contact with the bottom plate by means of nuts 15 working on threaded studs 16, the lower ends of which are secured to the bottom plate in any appropriate manner, the studs extending upwardly through apertures in the flat core terminals provided for that purpose. Soldering the lower ends or heads of the studs 16 to the upper side of the copper bottom plate has the advantage of giving a perfectly smooth uninterrupted pressing surface on the under side of said plate. 95 Less desirably the studs may extend through

the bottom plate, suitable counter-sinks being provided in such case on the working surface of the bottom plate to receive the stud heads. The winding may be insulated 5 from the core by a wrapping of mica or the like (not shown); and short-circuiting of parts of the winding by contact with the copper bottom plate may be guarded against by means of an interposed layer or plate 17 10 of insulating material such as mica. Said winding, besides energizing the magnet, also furnishes the heat for the sad iron. Any kind of wire suitable for this purpose may be employed but in a typical example the 15 use of four layers of asbestos covered copper wire, 22 gage (B. & S.), with 110 turns in each layer, has given excellent results in practice. The ample heat conducting and dissipating means provided by the massive 20 iron core which has its flattened ends in good metallic contact with the copper bottom plate, provides for rapidly transferring to the pressing surface of the sad iron a considerable part of the heat developed in the 25 winding. But a still greater proportion of the heat is transmitted directly from the flat coil to the bottom plate through the intervening thin layer of mica. As a consequence 30 of the provision for rapid transfer of heat from the winding, it is feasible to use relatively fine copper wire for the winding and at the same time to employ a current as high as 7 amperes or more, without endangering the integrity of the winding. As a result 35 the winding provides ample heat both for pressing purposes and for heavy magnetization of the core. This arrangement constitutes an important feature of the invention in the preferred form here shown. It is not 40 intended, however, to limit the invention to this particular type of winding, since other wire, as for example the various alloy resistance wires commonly employed in electrical heating apparatus, may be used, 45 though to less advantage, in place of the fine copper winding here described. The arrangement here illustrated is especially desirable from the standpoint of economy, efficiency, and structural compactness.

50 Provision is made for connecting the winding to a source of current supply, and also for automatically interrupting such connection and deenergizing the magnet when the iron is to be lifted. Various arrangements can evidently be used for this purpose, but the construction illustrated has proved satisfactory in practical service and possesses certain advantageous characteristics.

55 In this construction, one end 18 of the winding 12 is brought directly to a terminal post or stud 19; while the other end 20 is connected indirectly, as will be explained, to a second terminal post or stud 21 and also 60 to a third terminal post or stud 22. These

terminal posts may be mounted in various ways, but a desirable method here shown consists in providing the slightly tapered lower portion of each post with a wrapping or bushing 23, of suitable insulating material, such as mica for example, whereby the post may be forced snugly into a tapered socket member 24, which may conveniently be formed integral with the iron core piece. 70

Interposed in the circuit between end 20 75 of the winding and terminal studs 21 and 22, is the separable contact device or circuit breaker heretofore referred to. The function of this device is to break the winding circuit automatically just as the sad iron is 80 about to be lifted, whereby the magnet is de-energized and only the dead weight of the iron has to be raised in moving it away from the iron buck, which latter is indicated dia-grammatically in Fig. 2 at 25. Another 85 function of the circuit breaker is to enable the current to be cut off automatically or otherwise, independently of the lifting of the iron, and thus to provide for regulating the heating effect of the winding 12. One 90 desirable arrangement for effecting this will be explained in detail later.

The device for making and breaking the circuit through the winding 12 may take various forms, but that here illustrated has 95 been found particularly suitable in practice. The device comprises two relatively movable contacts, of which the lower contact is stationary in this instance, while the upper contact is movable. The lower contact con- 100 sists of a disk 26 having a stud or stem 27 and a head 28, all mounted on a horizontal arm 29 and insulated therefrom by insulating disks 30, 31 and insulating sleeve 32. The horizontal bar 29 is fastened by means 105 of screws 33 to a boss 34 on the pole piece 14 of the magnetic casting. Secured between the head 28 of the lower contact and insulating disk 31 is a conductive washer 35 which has two lugs or extensions 36 and 37, terminal 20 of the winding 12 being connected to lug 36, while wire 38 connects lug 37 with terminal stud 22.

The upper or movable contact is similar in form to the lower contact, consisting of disk 115 39, stem 40 and head 41, the contact being mounted by means of insulating disks 42, 43 and insulating sleeve 44 on arm 45 of a bell crank lever to be more fully described later. The conductive washer 46 is clamped be- 120 tween the head 41 of the upper contact and insulating disk 42, and it has a lug 47 from which wire 48 leads to terminal stud 21.

Leads 49 and 50 (Fig. 9) connect terminal studs 19 and 21, respectively, to direct cur- 125 rent mains 51; while condenser 52 is bridged across terminals 21 and 22 by means of a connection at 53 to lead 50, and by means of a lead 54 going to terminal 22. The con- 130 denser, which may be of 5 to 10 microfarads

capacity, for example, is provided to prevent arcing and resultant injurious heating and burning of the interrupter contacts; and it is here shown as entirely distinct, structurally, from the sad iron itself. It may of course be embodied in the sad iron construction, but this arrangement is less desirable as it increases the size of the sad iron. In some cases the condenser may advantageously be attached to the buck or support with which the sad iron is intended to be used. The leads 49, 50 and 54 may be combined in a single special cord with a special plug having sockets adapted to receive the upper ends of the terminal studs 19, 21 and 22, the stud ends and the corresponding plug sockets being unequally spaced apart whereby any error in attaching the plug is precluded.

Referring again to the mounting of the upper or movable contact of the make and break device, the movable supporting member 45 constitutes one arm of a bell crank lever which is pinned or otherwise secured to a longitudinal rocker shaft 55 arranged to one side of the center line of the sad iron, the other arm 56 of the bell crank lever extending upwardly through the cover 57 of the iron and terminating substantially over the center line thereof, at which point the handle grip 58 is secured. The rocker shaft 55 is mounted in bearings 59 and 60 which may be integral with the magnetic casting, and a collar 61, pinned to the shaft at 62, secures the shaft against displacement longitudinally. The handle is thus mounted for pivotal movement with respect to the sad iron body, which movement is utilized to make and break the circuit through the winding. While other handle constructions may obviously be used, that here illustrated has distinct mechanical advantages for the purposes of the invention.

The downward movement of the upper arm 56 of the bell crank lever which supports the handle is limited by abutment of the upper contact 39 against the lower or stationary contact 26; while the upward movement of the handle support 56 is limited by head 63 of an adjusting screw 64 which works in the internally threaded hollow boss 65 of the pole piece 14 of the magnetic casting. A lock nut 66 is provided to hold the adjusting screw in any adjusted position. In practice the permissible movement of the upper contact 39 relative to the lower contact 26 is most desirably limited to a very small distance. I have found that if this distance be as little as from .005 inch to .010 inch or a distance of about this order of magnitude, arcing may be entirely eliminated even where the current to be broken is relatively heavy. This manner of breaking the power circuit by limiting the gap to a distance of this small order of magnitude I

believe to be broadly novel, and the same forms the subject matter of my copending application Serial No. 231,840, filed May 1, 1918. In the present application, therefore, I do not claim broadly the application of this method to power circuit control. Nor is the construction and operation of the present apparatus limited to the use of a make and break device operating in this specific manner. But the use of a very small gap of the character mentioned is very desirable in the type of sad iron construction herein disclosed, and is preferred.

The cover 57, which incloses the principal operating parts of the sad iron construction, may be secured in position by means of cap nuts 66^a threading on the upper ends of posts 67, which may extend through the pole pieces 13 and 14 and be anchored to the copper bottom plate as by soldering or otherwise. An opening 68 is provided in the cover to accommodate the handle support 56 and to permit the slight movement thereof necessary to open and close the contacts of the make and break device. In order to prevent excessive pressure being brought to bear on the handle support, the handle may be provided with a vertical brace member 69 secured to the free end thereof, the lower end of this brace being received in a socket 70 which is arranged to limit further downward movement of the brace 69 after the contacts 39 and 26 are in firm engagement.

To enable easy assembly and disassembly the cover 57 is provided with a bulge 71 forming a rectangular window which is covered by an insulating cover 72 through which project the upper ends of terminal studs 19, 21 and 22, this insulating cover being held in place as by means of screws 73.

In the best form of the invention, provision is also made for controlling the temperature of the iron to a certain extent by making it optional with the operator whether current shall be supplied to the core winding during intervals when the iron is left alone between actual ironing periods, or only during said actual ironing periods. One way of accomplishing this is shown in the drawings, where 74 represents a button or knob having a stem 75 extending through the cover of the iron and grooved at 76 and 77. Depending upon the position of the stem, either groove 76 or 77 engages a hair pin spring 78 which may conveniently be made of piano wire. This spring is fastened to the underside of the cover by means of a plate 79 or other convenient means. Another plate 80 is fastened to the cover by means of distance collars 81 in such manner as to permit free play of the spring while at the same time acting as a stripper to prevent the hair pin spring from being moved downwardly when the button is pushed downward from engagement 76 to engage-

ment 77. The lower end of the button stem is threaded to engage a nut 82 mounted on the end of a flat spring 83, this latter being suitably secured to the collar 61 previously described as pinned on shaft 55. As shown, the nut 82 is provided with a deep counterbore 84, which enables easy engagement of the threaded lower end of the button stem with the nut after the iron is assembled. 10 When the knob is depressed into its lowest position as shown in Fig. 6, the flat spring 83 is given a downward deflection and the spring therefore tends normally to keep the contacts 26, 39 closed. It is evident therefore that when the iron is left alone with the knob depressed, the current continues to heat the iron. Should the temperature of the iron become too high or if the amount of heat developed during the actual ironing 20 periods is sufficient to maintain it at the proper temperature, the operator may pull the knob 74 into its upper position, thereby deflecting the spring to the position shown in dotted lines (Fig. 6), this position lying above the normal or unstressed intermediate position of the spring. When the knob is in its upper position, the spring operates, in the absence of downward pressure on the iron handle, to open the contacts 26, 39 and cut off the current to the winding, the circuit through the winding therefore being closed only during the actual 30 pressing periods.

It is to be noted that the position of the 35 knob 74 in no way affects or interferes with the automatic operation of the iron in so far as concerns the pressing and lifting forces exerted thereon by the operator. No matter which position the knob occupies, the current is always on when the iron handle is pressed down by the hand of the operator. If the knob is in its elevated position, downward pressure on the handle by the operator is only very slightly resisted by the relatively small pressure of the light spring 83, which is hardly perceptible to the operator. The current is always cut off when the operator exerts a lifting force on the handle, even if the knob be in its lower position. 50 The position of the knob therefore merely determines whether or not current shall be supplied to the winding when the iron is left alone and is untouched by the operator.

Some suitable form of thermostatic device 55 for automatically breaking the circuit when the temperature of the iron tends to exceed a certain predetermined maximum may be employed if desired, but as such device, in and of itself, forms no part of the present invention it is deemed unnecessary to illustrate the same.

The provision of a broad flat magnet coil 60 whose magnetic axis is substantially parallel to the base of the sad iron is especially advantageous, and this is particularly so when

the magnetic axis is also parallel to the longest dimension of said base, because the magnetic moment thereby produced is in the direction of the longest dimension of the iron. This reduces the stray field to a minimum and gives the maximum magnetic pull per pound of weight. 70

The operation of the sad iron and the method of using it are clear from the foregoing description. With the iron connected 75 to current supply mains as indicated in Fig. 9, the operator manipulates it just as he would an ordinary iron. A tailor, for example, lifts the iron from place to place on the cloth or suit to be pressed, and in so doing he breaks the winding circuit at the very outset of each lifting effort, thus de-energizing the magnet and consequently lifting only the dead weight of the sad iron. Upon setting the iron down on another spot, 80 he presses down slightly on the handle and thereby closes the circuit, energizing the magnet and setting up a heavy magnetic pull between the sad iron and the buck 25, which is constructed wholly or in part of 85 paramagnetic material, usually iron. For example, the buck may be a gas-heated iron buck of a type in common use with pressing machines at the present time. The goods or work to be pressed are indicated 90 diagrammatically at 25^a. For instance, in a typical example, a tailor's sad iron may be readily constructed in accordance with the invention to weigh about 7 pounds and to give an additional pressure of 21 pounds 100 by the action of the electromagnet therein. That is to say, the tailor gets all the advantages of a 28 pound iron, with the expenditure of no more physical labor than that required in using a 7 pound iron. The temperature of the iron may be controlled by means of the regulating knob as before described. 105

The broad principles underlying the invention can evidently be extended to pressing apparatus of various types, such as sad irons or the like, where the excess or artificial pressure is produced by means of agencies other than electricity, such as steam or compressed air. In such cases also, a common 110 control means, such as a handle, may serve both to move the pressing device toward or from the work to be pressed, and also to automatically operate controlling valves or other appropriate means whereby the operation of the power medium is started and stopped without attention from the operator, in a manner analogous to making and breaking the electromagnet circuit in the specific embodiment of the invention hereinbefore 115 described in detail.

In still another embodiment of the invention the pressing member itself, a gas-heated sad iron, for example, may be so heavy, or so heavily weighted, that the requisite de- 120 125

gree of pressure on the goods is obtained by the action of gravity alone. In such an embodiment of the invention, counterpoise mechanism is provided to which the sad iron 5 may be connected when it is desired to counterbalance the weight of the iron, as in lifting it; and from which the sad iron may be disconnected when it is desired to utilize the full weight of the iron in pressing.

10 The connection and disconnection may be effected electrically or otherwise and in a perfectly automatic manner by the acts of the operator in manipulating the sad iron. In this way it is possible to operate by hand 15 a sad iron of far greater weight than could be employed for manual operation heretofore.

Various changes can evidently be made in the herein-described constructions without 20 departing from the spirit of the invention defined in the appended claims.

What I claim is:

1. An electric sad iron comprising, in combination, a pressing or smoothing member, an electromagnet provided with suitable circuit connections whereby the magnet may be energized, and a handle for the iron automatically operable by variations in pressure to vary said circuit connections.

30 2. An electric sad iron comprising, in combination a body portion containing an electromagnet provided with suitable circuit connections whereby the magnet may be energized, and a handle for the iron automatically operable by variation in pressure to vary 35 said circuit connections, downward pressure on the handle being effective to close the circuit through the electromagnet, and an upward pull on the handle being effective 40 to open said circuit.

3. An electric sad iron comprising a body portion containing an electromagnet provided with suitable circuit connections whereby it may be energized, a make and 45 break device in said circuit connections, and a handle mounted on said body and controlling said make and break device, the arrangement being such that the electromagnet circuit is automatically broken by lifting 50 pressure on the handle.

4. An electric sad iron provided with electromagnetic means adapted, when energized, to produce pressure between the sad iron and a suitable support or abutment, and controlling means operable to make or break connection between said electromagnetic means and a source of current supply, said controlling means being arranged to break the connection automatically upon suitable application 55 to said iron of force tending to move the iron away from such support or abutment.

5. A sad iron provided with an electromagnet adapted, when energized, to produce 60 pressure between said iron and a suitable

paramagnetic buck or support, and means controlling the energization of said electromagnet, said means being arranged to automatically deenergize the electromagnet when a lifting force is suitably exerted on the iron. 70

6. A sad iron provided with an electromagnet adapted, when energized, to produce pressure between said iron and a suitable paramagnetic buck or support, circuit connections whereby the electromagnet may be 75 energized, and a handle for the iron, said handle being arranged to open the circuit connections when a lifting force is suitably exerted on the handle.

7. An electric sad iron comprising a bottom plate of heat conductive diamagnetic material, a paramagnetic core having its axis disposed substantially parallel with and in close proximity to said bottom plate and having its ends in contact therewith, and 80 suitable windings for the core.

8. An electric sad iron comprising a bottom plate of copper or the like, a broad flat iron core having its axis arranged parallel to and closely adjacent the upper side of said plate 90 and having ends making good contact therewith, and suitable electrical windings for the core.

9. An electric sad iron comprising a bottom plate and a heating element arranged 95 above and in close proximity thereto, said heating element consisting of a suitably disposed small gage conductor of a highly conductive metal.

10. An electric sad iron comprising a bottom plate of a highly conductive metal, and a heating element, consisting of a flat coil of fine insulated copper wire, arranged above and in close proximity to said bottom plate.

11. An electric sad iron comprising a bottom plate of a highly conductive metal, a conductive metal core mounted on the upper side of said plate in metallic contact therewith, and a winding of fine insulated 110 copper wire on said core.

12. An electric heating device comprising a heating element consisting of a relatively small gage metal conductor having a conductivity at least substantially as high as 115 that of copper, in combination with a heat transferring member arranged in close proximity to said heating element and capable of conducting heat away therefrom sufficiently fast to prevent fusion of said element.

13. An electric heating device comprising small gage copper wire wound on a large capacity heat transferring core of metal having high heat conductivity, the winding 120 being suitably insulated from said core.

14. An electric sad iron comprising, in combination, a bottom or pressure plate of diamagnetic material, a broad iron core mounted above and close to the bottom plate 125

and in metallic contact therewith at the core poles or ends, a winding on said core, terminals whereby current may be supplied to said winding, and a make and break device 5 in circuit with the winding, said make and break device being automatically operable by exertion of suitable lifting force on the sad iron to open the winding circuit.

15. An electric sad iron comprising, in 10 combination, a bottom or pressure plate of diamagnetic material, a broad iron core mounted above and close to the bottom plate and in metallic contact therewith at the core poles or ends, a winding on said core, terminals whereby current may be supplied to 15 said winding, and a controlling device in circuit with the winding, said controlling device being automatically operable by suitable application of a lifting force on the sad 20 iron to decrease the flow of current through said winding.

16. An electric sad iron comprising, in combination, a highly conductive metal bottom plate, a flat iron core member arranged 25 close above said plate and having its ends or poles in metallic contact therewith, a heating and magnetizing winding on said core, means whereby said winding may be connected to a source of current supply, a 30 make and break device in circuit with the winding, and a handle, said handle being mechanically connected to the make and break device and operating, when the iron is lifted by the handle, to break the circuit 35 through the winding.

17. An electric sad iron comprising, in combination, an electromagnet having a suitable energizing winding, a make and break device comprising a pair of relatively 40 movable contacts in circuit with said winding, a bell crank lever eccentrically pivoted to the sad iron, one arm of said lever carrying one of said contacts, and a lifting handle attached to the other arm of the lever, the 45 arrangement being such that downward pressure on said handle forces the contacts together while an upward pull on the handle separates them.

18. In combination, a sad iron body, a 50 directing handle movably secured thereto, and power means for forcing the sad iron against work to be pressed, the operation of said power means being controlled by moving said handle.

55 19. In combination, a sad iron body having a handle pivoted thereto, and power means for forcing the sad iron against work to be pressed, pivotal movement of the handle being effective to put said power 60 means in or out of operation.

20. In an electric sad iron, the combination, with a suitable winding and current-supply terminals therefor, of a make and break device in circuit with said winding 65 comprising relatively movable contacts, the

relative movement of said contacts being limited to between approximately .005 inch and .010 inch; substantially as described.

21. Pressing apparatus comprising, in combination, a pressing member, means 70 whereby said member may be moved into and out of pressing position, and power means rendered operable by the first-named means to cause said pressing member to exert or cease to exert pressure at any desired 75 time during the operation of said pressing member.

22. Pressing apparatus comprising, in combination, a pressing member, power means operable to force said pressing member 80 against work to be pressed, and directing means whereby said pressing member may be moved toward and away from the work, said directing means being freely 85 movable a limited amount relatively to said pressing member to control said power means.

23. Pressing apparatus comprising in combination, a pressing member, a handle whereby said member may be moved toward 90 or away from work to be pressed, and power means operable to force said pressing member against the work, said handle being freely movable a limited distance for controlling said power means. 95

24. Pressing apparatus comprising, in combination, a pressing member, directing means for moving the pressing member into and out of contact with work to be pressed, and power means operable to force the pressing member against the work, said directing means being arranged to automatically actuate said power means after the pressing member has been moved into contact with the work, and to automatically throw said 105 power means out of operation when force tending to move the pressing member away from the work is applied to said directing means.

25. Pressing apparatus comprising, in combination, a pressing member, power means operable to force the pressing member against work to be pressed, and common means both for moving the pressing member toward and away from the work and for rendering said power means effective or ineffective, respectively, upon engaging or disengaging the work. 110

26. A sad iron comprising, in combination with a suitable pressing member, an 115 electromagnet adapted and arranged to cooperate with a magnetic buck or support in producing a magnetic pull of the iron toward such buck and thereby increasing the effective working pressure of said pressing 120 member, and means for automatically decreasing said magnetic pull when force is suitably exerted to move the iron away from the work.

27. A sad iron comprising, in combina- 130

tion with a suitable pressing member, an electromagnet adapted and arranged to co-operate with a magnetic buck or support in producing a magnetic pull of the iron toward such buck and thereby increasing the effective working pressure of said pressing member, and means for automatically eliminating said magnetic pull when force is suitably exerted to move the iron away from the work.

28. The combination, with a buck or support composed at least in part of paramagnetic material, of a press or sad iron provided with an electromagnet adapted to operate with said buck to produce a magnetic pull between the iron and the buck, and means for automatically eliminating or suitably decreasing such pull when the iron is about to be moved away from the buck.

29. A said iron provided with electromagnetic means for increasing the effective pressure of the sad iron when it is used in conjunction with a paramagnetic buck or support, the electromagnetic means being so arranged that the magnetic moment produced thereby is in the direction of the longest dimension of the iron.

30. A sad iron provided with an electro-

magnet having a broad flat energizing coil whose axis is substantially parallel to the base of the sad iron.

31. An electric sad iron comprising, in combination, a winding arranged to heat the iron and also to increase the working pressure thereof electromagnetically, means whereby the winding circuit is closed and opened automatically in moving the sad iron into or out of contact with work to be pressed, and means adjustable to maintain the circuit either open or closed when the sad iron is not being manipulated.

32. Pressing apparatus comprising, in combination, a pressing member adapted to exert pressure on work such as cloth and the like, and manual control means whereby an operator may move said pressing member toward and away from such work, said manual control means being operable by the acts of the operator in moving the pressing member to automatically eliminate or neutralize at least a substantial portion of the pressure-producing force during the intervals between actual pressing periods.

In testimony whereof I hereunto affix my signature.

FRITZ LOWENSTEIN.
